Civpower Neck Fan: Portable Personal Neck Cooling Rechargeable Bladeless Fan—Hands Free 3 Speed 4000 mAh Battery USB Operated Wearable Headphone Design—for Men Women Outdoor Indoor White; Date First Available: Apr. 14, 2021; <https://www.amazon.com/CIVPOWER-360%C2%B0Cooling-Adjustment-Rechargeable> (Year: 2021).*

Primary Examiner — George J Ulsh*Assistant Examiner* — Andrea Marie McKay(74) *Attorney, Agent, or Firm* — Nitin Kaushik(57) **CLAIM**

The ornamental design for a neck fan, as shown and described.

DESCRIPTION

FIG. 1 is a front, top and right side perspective view of a neck fan, showing my new design;

FIG. 2 is a rear, bottom and left side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the neck fan that form no part of the claimed design.
